BREATHING APPARATUS

Philip R. Nourse, Los Angeles, and Robert Kimes, Culver City, Calif., assignors to The Garrett Corporation, Los Angeles, Calif., a corporation of California

Application January 28, 1952, Serial No. 268,516

17 Claims. (Cl. 128—142)

This invention relates to apparatus for regulating the delivery of a breathable gas.

This invention has particular utility in sport, emergency and construction diving, and it will be described in relation to such submarine uses. It will be understood, however, that the device may be used in connection with breathing at high altitudes and/or in a contaminated atmosphere. It also may be employed in the therapeutic administration of oxygen or breathing mixtures.

When diving in depths up to approximately 300 feet, and whenever a diver intends to spend a period of time under water, it is necessary that a supply of air be provided for him in a reliable and comfortable manner. The apparatus used to regulate the air must be simple and rugged in construction, and it should present low resistance to breathing in order to prevent excessive fatigue. In the instant device air is supplied from a high pressure source and is suitably controlled so that it reaches the diver at a reduced pressure, determined and governed by the pressure of the ambient fluid medium.

It is therefore one object of the present invention to provide an improved regulating device which is adapted to supply a breathable gas or gaseous mixture to an individual at a pressure commensurate with the pressure of the surrounding fluid medium.

Another object of the invention is to provide an improved arrangement of parts in a regulating apparatus so that the regulator will be "fail-safe" in its construction and mode of operation.

A further object of the invention is to provide a novel regulating apparatus that is compact, and that can, if desired, be of very light weight and which contains few parts, thus to constitute a relatively inexpensive unit giving adequate and positive control of the delivery of a breathable gas.

A further object of the invention is to provide a novel regulating apparatus having a single chamber positioned in a single conduit for the delivery of a breathable gas to an individual.

A still further object of the invention is to provide a novel inlet valve actuating mechanism, operable in response to respiration-induced changes in the pressure in a chamber housing said valve, and of such construction as to reduce breathing fatigue to a minimum.

Another object of the invention is to provide, in a regulating apparatus, a novel flexible diaphragm and exhalation valve structure.

Other and further important objects of the invention will become apparent in the following description and appended claims, and in the accompanying drawing, wherein:

Fig. 1 is a transverse view of the regulating apparatus, partially in section and shown connected to a storage cylinder and a breathing mouthpiece;

Fig. 2 is a transverse section taken as indicated by the line 2—2 of Fig. 1; and

Fig. 3 is an enlarged fragmentary sectional view of an inlet valve.

Referring primarily to Fig. 1, the regulator is indicated generally at 10 and includes a body 11 and a cap 12. A flexible diaphragm 13 is secured between the body and the cap by means of spaced screws 14 and provides a movable wall at one side of a chamber 15 formed in the body.

The regulator is shown as mounted on and secured to a cylinder 16, said cylinder having a standard shut-off

2

valve mechanism 17 and a fitting 18. A nut 19, rotatably received on a nipple 20 is threadably secured to the fitting 18, a passage 21 in the fitting communicating with a bore 22 in the nipple. A suitable seal 23 is provided between the fitting and the nipple, and a tubular insert 24 is threadably received in the end of the bore 22 to retain a filter screen 25 therein.

The nipple 20 is threadably received in a boss 26 formed on the body 11 and extends into the chamber 15. A set screw 27, threadably received at the side of the boss 26, engages the threads of the nipple 20. A counterbore 28 is provided in the upper end of the nipple and receives an insert 29, said insert being provided with an orifice 30, Fig. 3, which communicates with an enlarged bore 31 of substantially the same diameter of the bore 22.

The body 11 is further provided with raised pedestals 32 which extend into the chamber 15 and have peripheral notches 33 which receive an annular plate 34, said plate being secured to the pedestals 32 by means of screws 35. The plate 34 has a central opening 36 which slidably receives a valve stem 37, of an inlet valve, indicated generally at 38. The stem 37 is provided, at its lower end, with an enlargement 39 which carries a cone-shaped end 40, of "nylon" or other suitable material, which is adapted to co-act with the orifice 30 in the insert 29. The upper end of the valve stem 37 is provided with a washer 41, of greater diameter than the stem, which is secured thereon by means of a screw 42 threadably received in the end of the stem. A compression spring 43 is positioned about the stem and co-acts with the plate 34 and the enlargement 39 to urge the valve 38 in a closing direction.

The diaphragm 13 is provided with upper and lower plates 44 and 45 which are secured thereto as by rivets 46. The lower plate 45 is adapted to be engaged by three spaced, actuating fingers 47, the lower ends of which are received in notches 48 in an annular rim 49 formed integrally with the plate 34 and surrounding the upper portion of the valve stem 37 and the washer 41. The fingers 47 have their ends 50 bent back, the ends of the bent back portions being adapted to engage the inner surface of the rim 49 adjacent the notches 48, so that the fingers 47 may be inserted beneath the washer 41 and pivotally positioned in the notches 48 to be thereby retained therein. The fingers 47 are suitably curved as at 51 to provide a smooth, low friction engagement with the plate 45 of the diaphragm. It is to be noted that the arrangement of the valve actuating mechanism, comprising the fingers 47, diaphragm plate 45 and washer 41, is such that it provides a large mechanical advantage for opening the valve 38, and engagement of the fingers with the diaphragm at points adjacent the outer periphery thereof also insures a stable movement of the diaphragm, preventing tipping thereof and enabling the use of a light spring 42 to thus reduce breathing fatigue to a minimum.

To provide a zero differential of hydrostatic head over exhalation pressure, a flexible exhalation valve indicated generally at 52 is provided directly on and in the approximate center of the diaphragm 13. The exhalation valve 52 includes a flexible valve member 53 having a raised central portion 54, the member 53 being secured to the diaphragm 13 by means of a rivet 55 or any other suitable attachment means. The member 53 is adapted to normally occlude a plurality of apertures 56, through the plates 44 and 45 and the diaphragm 13, arranged in spaced radial relationship about the rivet 55. To limit outward movement of the diaphragm 13 and the exhalation valve 52, an internal boss 57 is provided in the cap 12, adapted to engage the raised portion 54 of the valve member 51. The cap 12 is further provided with spaced radial openings 58 for the admission of the ambient fluid medium (the atmosphere, or water) into the interior of the cap. The pressure of the ambient fluid medium will therefore act against the outer surface of the diaphragm 13 and the valve member 53.

The body 11 is provided with a fitting 59 which contains a passage 60 communicating between the chamber 15 and a flexible hose 61 for the delivery of the regulated breathable gas from the valve 10 to a person. The hose 61 is clamped to the fitting 59, as at 62 and

extends to an elbow 63 which supports a resilient mouthpiece 64, the mouthpiece being adapted to fit behind the lips of the individual and to be retained there by clamping the teeth against resilient protuberances 65.

In use, the cylinder 16, charged to a pressure of approximately 2200 p. s. i., is usually strapped to the back of the individual. In order that there be no differential between the pneumatic pressure in the chamber 15 and the pressure in the lungs of the individual, the cylinder 16 is preferably so-disposed that the regulator 10 is located at a position approximating the level of the lungs. After opening the valve 17 and placing the mouthpiece 64 in the mouth, breathing of the compressed gas may be started. Upon submersion, hydrostatic pressure will be immediately admitted through the regulator openings 58 and against the diaphragm 13, to cause it to move inwardly toward the chamber 15, depressing the actuating fingers 47, raising the valve stem 37 from its seat in the insert 29, and permitting the flow of the breathable gas through the passages 21, 22, bore 31 and orifice 30 and into the chamber 15. This flow into the chamber 15 continues until the pressure of the gas within the chamber 15 overcomes the hydrostatic pressure acting on the opposite side of the diaphragm 13, whereupon the diaphragm will be moved outwardly from the chamber 15 and the valve 38 will close.

Upon inhalation, gas pressure within the chamber 15 will be reduced, causing the diaphragm 13 to move toward the chamber 15, opening the valve 38 and admitting additional gas from the cylinder 16. It is to be noted that inasmuch as the pressure within the chamber 15 is governed by the pressure of the ambient fluid medium acting on the outer side of the diaphragm, the breathable gas delivered to the individual will be maintained at a pressure equaling that of the external pressure acting on him, regardless of the depth of submersion.

Upon exhalation, the pressure within the chamber 15 will be increased above the ambient hydrostatic pressure, thus forcing the diaphragm 13 outwardly until the boss 57 is contacted by the portion 54 of the flexible valve member 53, whereupon the valve member 53 will be peripherally flexed away from its occlusion of the apertures 56, as shown by the dotted lines in Fig. 1, to permit a flow of exhalation products from the chamber 15 through the apertures 56 and out into the surrounding fluid medium through the openings 58. The inhalation-exhalation cycle may then be repeated until the compressed gas in the cylinder 16 is expended.

It will be noted that if, for any reason such as, for example, the breakage of the compression spring 42 about the valve stem 37, the valve 38 should remain open, the regulator will "fail-safe" due to the relative sizes of the orifice 30 and the exhaust apertures 56, their size ratio being such that the pressure in the chamber 15 will be maintained at a breathable level even though the flow from the pressure source will be continuous.

Having thus described the invention and the present improvement thereof, it is desired to emphasize the fact that many modifications may be resorted to in a manner limited only by a just interpretation of the following claims.

We claim:

1. A breathable gas regulating apparatus comprising: a source of breathable gas; conduit means for conducting said gas to a point of use; a regulator positioned in said conduit means, said regulator having a chamber and a respiration responsive diaphragm forming a movable wall thereof, one side of said diaphragm being exposed to the pressure of a surrounding fluid medium; a normally closed exhalation valve carried by said diaphragm; and a breathable gas inlet valve operably associated with said diaphragm whereby said inlet valve will be opened in response to an inhalation produced reduction in chamber pressure below the pressure of said fluid medium.

2. A breathable gas regulating apparatus comprising: a source of compressed breathable gas; conduit means for conducting the gas to a point of use; a regulator positioned in said conduit means, said regulator having a chamber and a respiration responsive diaphragm forming a movable wall thereof, one side of said diaphragm being exposed to chamber pressure, the other side of

said diaphragm being exposed to the pressure of a surrounding fluid medium; a normally closed exhalation valve carried by and positioned at the approximate center of area of said diaphragm; and a breathable gas inlet valve operably associated with said diaphragm whereby said inlet valve will be opened in response to an inhalation produced reduction in chamber pressure below the pressure of said fluid medium.

3. A breathable gas regulating apparatus comprising: 10 a source of compressed breathable gas; conduit means for conducting said gas to a point of use; a regulator positioned in said conduit means, said regulator having a chamber and a respiration responsive diaphragm forming a movable wall thereof, one side of said diaphragm being exposed to chamber pressure, the other side of said diaphragm being exposed to the pressure of a surrounding fluid medium; a normally closed exhalation valve carried by said diaphragm; a breathable gas inlet valve positioned in said chamber; and lever means operably connecting said diaphragm and said inlet valve whereby said inlet valve will be opened in response to an inhalation produced reduction in chamber pressure below the pressure of said fluid medium.

4. A breathable gas regulating apparatus comprising: 25 a source of compressed breathable gas; conduit means for conducting said gas to a point of use; a regulator positioned in said conduit means, said regulator having a chamber and a respiration responsive diaphragm forming a movable wall thereof, one side of said diaphragm being exposed to chamber pressure, the other side of said diaphragm being exposed to the pressure of a surrounding fluid medium; a normally closed exhalation valve carried by and positioned in the approximate center of area of said diaphragm; a breathable gas inlet valve positioned in said chamber; and lever means operably connecting said diaphragm and said inlet valve whereby said inlet valve will be opened in response to an inhalation produced reduction in chamber pressure below the pressure of said fluid medium.

5. A breathable gas regulating apparatus comprising: 40 a body having a chamber; a respiration responsive diaphragm forming a movable wall for said chamber; an inlet to said chamber for a compressed breathable gas, one side of said diaphragm being exposed to the pressure of said gas in said chamber, the other side of said diaphragm being exposed to the pressure of an ambient fluid medium; a passage from said chamber for delivery of said gas to a point of use and for return of exhalation products to said chamber; an inlet valve positioned in said chamber and normally occluding said chamber inlet, said inlet valve being operably associated with said diaphragm and adapted to be opened in response to an inhalation produced reduction in pressure in said chamber; and a normally closed exhalation valve carried by said diaphragm.

6. A breathable gas regulating apparatus comprising: 45 a body having a chamber and a respiration responsive diaphragm forming a movable wall for said chamber; an inlet to said chamber for a compressed breathable gas, one side of said diaphragm being exposed to the pressure of said gas in said chamber, the other side of said diaphragm being exposed to the pressure of an ambient fluid medium, a passage from said chamber for delivery of said gas to a point of use and for return of exhalation products to said chamber; an inlet valve positioned in said chamber and normally occluding said chamber inlet, said inlet valve being operably associated with said diaphragm and adapted to be opened in response to an inhalation produced reduction in pressure in said chamber; a normally closed exhalation valve carried by said diaphragm; and means to limit movement of said diaphragm away from said chamber.

7. A breathable gas regulating apparatus comprising: 50 a body having a chamber and a respiration responsive diaphragm forming a movable wall for said chamber; an inlet to said chamber for a compressed breathable gas, one side of said diaphragm being exposed to the pressure of said gas in said chamber, the other side of said diaphragm being exposed to the pressure of an ambient fluid medium; a passage from said chamber for delivery of said gas to a point of use and for return of exhalation products to said chamber; an inlet valve positioned in said chamber and normally occluding said chamber inlet, said inlet valve being operably associated with said diaphragm and adapted to be opened in response to an

inhalation produced reduction in pressure in said chamber; a port through said diaphragm adjacent the center of area thereof; and a flexible exhalation valve member carried by said diaphragm and positioned to normally occlude said port, thereby permitting flow only outwardly from said chamber.

8. A breathable gas regulating apparatus comprising: a body having a chamber and a respiration responsive diaphragm forming a movable wall for said chamber; an inlet to said chamber for a compressed breathable gas, one side of said diaphragm being exposed to the pressure of said gas in said chamber, the other side of said diaphragm being exposed to the pressure of an ambient fluid medium; a passage from said chamber for delivery of said gas to a point of use and for return of exhalation products to said chamber; an inlet valve positioned in said chamber and normally occluding said chamber inlet, said inlet valve being operably associated with said diaphragm and adapted to be opened in response to an inhalation produced reduction in pressure in said chamber; a port through said diaphragm adjacent the center of area thereof; a flexible exhalation valve member carried by said diaphragm and positioned to normally occlude said port thereby permitting flow only outwardly from said chamber; and means to limit movement of said diaphragm away from said chamber.

9. In a submarine breathing apparatus: a single chamber adapted to be positioned in a single conduit, said conduit being connected with a supply of breathable gas under pressure and with the breathing system of a person being served; a respiration responsive flexible diaphragm forming a movable wall of said chamber, said diaphragm being centrally provided with a normally closed exhalation valve to permit fluid flow only outwardly from said chamber; said diaphragm and said exhalation valve being exposed on one side to the pressure of a surrounding fluid medium and on the other side to the pressure of the gas in said chamber; an inlet valve member within said chamber adapted to control the delivery of said gas thereto; and actuating fingers movable by said diaphragm to operate said inlet valve member in response to variations in pressure in said chamber.

10. In a submarine breathing apparatus: a single chamber adapted to be positioned in a single conduit, said conduit being connected with a supply of breathable gas under pressure and with the breathing system of a person being served; a respiration responsive flexible diaphragm forming a movable wall of said chamber, said diaphragm being centrally provided with a normally closed exhalation valve to permit fluid flow only outwardly from said chamber; said diaphragm and said exhalation valve being exposed on one side to the pressure of a surrounding fluid medium and on the other side to the pressure of the gas in said chamber; an inlet valve member within said chamber adapted to control the delivery of said gas thereto; actuating fingers movable by said diaphragm to operate said inlet valve member in response to variations in pressure in said chamber; and means engaging said exhalation valve to limit outward movement of said diaphragm.

11. A breathable gas demand regulator comprising in combination: a body and a cap; a respiration responsive movable diaphragm secured between said body and said cap, one side of said diaphragm being exposed to a surrounding fluid medium admitted through said cap, the other side of said diaphragm being exposed to the pressure of said breathable gas within a chamber formed in said body; a passage from said chamber for delivery of said gas to a point of use and for return of exhalation products to said chamber; a normally closed exhalation valve carried by and positioned in substantially the center of area of said diaphragm, fluid flow therethrough being permitted only outwardly from said chamber; a stop within said cap and engageable by said exhalation valve to limit movement of said diaphragm toward said cap; an inlet valve positioned to occlude an orifice, said orifice providing restricted inlet for the admittance of said breathable gas into said chamber, said inlet valve extending into said chamber, normally urged in a closing direction and having an enlarged head thereon; a raised rim spaced from and surrounding said enlarged valve head; and a plurality of arms engageable with one side of said diaphragm, pivoted on said rim and extended under said enlarged valve head, movement of said diaphragm

toward said chamber being adapted to open said valve and permit said breathable gas to flow into said chamber.

12. A breathable gas demand regulator comprising in combination: a body and a cap; a respiration responsive movable diaphragm secured between said body and said cap, one side of said diaphragm being exposed to a surrounding fluid medium admitted through said cap, the other side of said diaphragm being exposed to the pressure of said breathable gas within a chamber formed in said body; a passage from said chamber for delivery of said gas to a point of use and for return of exhalation products to said chamber; a plurality of ports through said diaphragm adjacent the center of area thereof; a flexible exhalation valve member carried by said diaphragm and positioned to normally occlude said ports thereby permitting fluid flow only outwardly from said chamber; a stop within said cap and engageable by said exhalation valve member prior to the opening of said valve to limit movement of said diaphragm toward said cap; restricted inlet valve positioned to occlude an orifice, said orifice providing an inlet for the admittance of said breathable gas into said chamber, said inlet valve extending into said chamber, normally being urged in a closing direction and having an enlarged head thereon; a stationary raised rim spaced from and surrounding said enlarged valve head; and a plurality of arms engageable with one side of said diaphragm adjacent the outer periphery thereof, pivoted on said rim and extended under said enlarged valve head, movement of said diaphragm toward said chamber being adapted to open said valve and permit said breathable gas to flow into said chamber.

13. A breathable gas regulating apparatus comprising: a source of breathable gas; passage means for conducting said gas from said source to a point of use; a valve for controlling the flow of said breathable gas through said passage means; a respiration responsive diaphragm, said diaphragm being exposed on one side to the pressure of a surrounding fluid medium and on the other side to the pressure of said gas existing at said point of use; spring means normally urging said valve toward a closed position; a plurality of spaced arms engageable with said diaphragm adjacent the periphery thereof and extending to said valve; means for operably connecting said arms with said valve whereby, upon movement of said diaphragm by an inhalation produced reduction in pressure adjacent said other side thereof, said valve will be opened to permit flow of said breathable gas through said passage means to said point of use; and a normally closed exhalation valve carried by said diaphragm and adapted to be opened in response to an exhalation produced rise in pressure adjacent said other side of said diaphragm.

14. A breathable gas regulating apparatus comprising: a source of breathable gas; passage means for conducting said gas from said source to a point of use; an orifice in said passage means; a valve adapted to cooperate with said orifice for controlling the flow of said breathable gas through said passage means; a respiration responsive diaphragm, said diaphragm being exposed on one side to the pressure of a surrounding fluid medium and on the other side to the pressure of said gas existing at said point of use; spring means normally urging said valve toward a closed position; a plurality of spaced arms engageable with said diaphragm adjacent the periphery thereof and extending to said valve; an enlarged head on said valve; a stationary raised rim spaced from and surrounding said enlarged head, said spaced arms being pivoted on said rim and extending under said enlarged head whereby, upon movement of said diaphragm by an inhalation produced reduction in pressure adjacent said other side thereof, said valve will be opened to permit flow of said breathable gas through said passage means to said point of use; and a normally closed exhalation valve carried by said diaphragm and adapted to be opened in response to an exhalation produced rise in pressure adjacent said other side of said diaphragm.

15. A breathable gas regulating apparatus comprising: a source of breathable gas; passage means for conducting said gas from said source to a point of use; a valve for controlling the flow of said breathable gas through said passage means; a respiration responsive diaphragm, said diaphragm being exposed on one side to the pressure of a surrounding fluid medium and on the other side to

the pressure of said gas existing at said point of use; spring means normally urging said valve toward a closed position; three equally spaced arms engageable with said diaphragm adjacent the periphery thereof and extending to said valve; an enlarged head on said valve; a stationary raised rim spaced from and surrounding said enlarged head, said spaced arms being pivoted on said raised rim and extending under said enlarged head whereby, upon movement of said diaphragm by an inhalation produced reduction in pressure adjacent said other side thereof, said valve will be opened to permit flow of said breathable gas through said passage means to said point of use; and a normally closed exhalation valve carried by said diaphragm and adapted to be opened in response to an exhalation produced rise in pressure adjacent said other side of said diaphragm.

16. A breathable gas regulating apparatus comprising: a source of breathable gas; passage means for conducting said gas from said source to a point of use; a valve for controlling the flow of said breathable gas through said passage means; a respiration responsive diaphragm, said diaphragm being exposed on one side to the pressure of a surrounding fluid medium and on the other side to the pressure of said gas existing at said point of use; spring means normally urging said valve toward a closed position; three equally spaced arms engageable with said diaphragm adjacent the periphery thereof and extending to said valve; an enlarged head on said valve; a stationary raised rim spaced from and surrounding said enlarged head; bent back portions formed on ends of said spaced arms, said spaced arms being pivoted on said raised rim with said bent back portions extending under said enlarged head whereby, upon movement of said diaphragm by an inhalation produced reduction in pressure adjacent said other side thereof, said valve will be opened to permit flow of said breathable gas through said passage means to said point of use; and a normally closed exhalation valve carried by said diaphragm and adapted to be opened in response to an exhalation produced rise in pressure adjacent said other side of said diaphragm.

17. A breathable gas regulating apparatus comprising:

5 a source of breathable gas; passage means for conducting said gas from said source to a point of use; a valve for controlling the flow of said breathable gas through said passage means; a respiration responsive diaphragm, said diaphragm being exposed on one side to the pressure of a surrounding fluid medium and on the other side to the pressure of said gas existing at said point of use; spring means normally urging said valve toward a closed position; a plurality of spaced arms engageable with said diaphragm adjacent the periphery thereof and extending to said valve; an enlarged head on said valve; a stationary raised rim spaced from and surrounding said enlarged head; a plurality of notches in said raised rim; bent back portions formed on ends of said spaced arms, said spaced arms being pivoted in said notches on said raised rim with said bent back portions extending under said enlarged head and engaging an inside wall of said raised rim to prevent radial displacement of said arms whereby, upon movement of said diaphragm by an inhalation produced reduction in pressure adjacent said other side thereof, said valve will be opened to permit flow of said breathable gas through said passage means to said point of use; and a normally closed exhalation valve carried by said diaphragm and adapted to be opened in response to an inhalation produced rise in pressure adjacent said other side of said diaphragm.
